(57) **CLAIM**

The ornamental design for a footwear upper, as shown and described.

DESCRIPTION

FIG. 1 is a perspective view of the footwear upper; FIG. 2 is a top view thereof;

FIG. 3 is a right side view thereof;

FIG. 4 is a left side view thereof;

FIG. 5 is a front view thereof; and,

FIG. 6 is a rear view thereof.

FIGS. 1-6 include broken lines (dash-dash format) that represent stitching, which is part of the claimed design. FIGS. 1-6 show portions of an article of footwear in phantom lines (long dash-short dash-short dash format). The article of footwear portions illustrated in phantom lines are shown for environmental purposes and do not form any part of the claimed design. Further, the phantom lines immediately adjacent the solid-line portions of the design form the boundary of the design, with the phantom lines forming no part of the claimed design.

FIGS. 1-12 and 14 include broken lines (dash-dash format) that represent stitching, which is part of the claimed design. FIGS. 1-14 show portions of an article of footwear in phantom lines (long dash-short dash-short dash format). The article of footwear portions illustrated in phantom lines are shown for environmental purposes and do not form any part of the claimed design. Further, the phantom lines immediately adjacent the solid-line portions of the design form the boundary of the design, with the phantom lines forming no part of the claimed design.
